DESIGN FOR A LAWN MOWER HANDLE

Marlowe H. Kluter, Richmond, Ind., assignor to
The F. & N. Lawn Mower Company, Richmond,
Ind., a corporation of Delaware

Application February 10, 1940, Serial No. 90,190

Term of patent 14 years

To all whom it may concern:

Be it known that I, Marlowe H. Kluter, a citizen of the United States of America, residing at Richmond, in the county of Wayne and State of Indiana, have invented a new, original, and ornamental Design for a Lawn Mower Handle, of which the following is a specification, reference being had to the accompanying drawing, forming part thereof.

Figs. 1 and 2 of the drawing are a front view and a side view, respectively, of a lawn mower handle embodying the design.

Fig. 3 is a sectional view of the handle shown in Figs. 1 and 2 taken substantially on line 3—3 of Fig. 1.

I claim:

The ornamental design for a lawn mower handle, as shown.
